BILGE PUMP

Thomas Langan, Annapolis, Md.

Application November 9, 1944, Serial No. 562,654

2 Claims. (Cl. 103—150)

This invention relates to deformable chamber pumps and, more particularly, to pumps of the diaphragm type.

The primary object of the invention is to provide a manually operable pump capable of handling large volumes of water where speed, simplicity in operation, compactness and ruggedness are of the essence. These requirements seem to congregate in the bilges of boats wherein all too frequently the bilgewater is not noticed until it has become a demonstrated hazard.

To meet the above requirements, it is intended to provide a pump having a low intake and delivery tube-like box, having intake and exhaust flap valves spaced therealong and operating in the same direction, a relatively large chamber having a large diaphragm, and a relatively small diameter conduit connecting the chamber and the portion of the box between the valves whereby, when the diaphragm is lifted upwardly to expand the chamber, the exhaust valve is pulled closed and water is driven under atmospheric pressure through the intake valve and when the diaphragm is driven down to compress the chamber, the intake valve is closed and the water is driven out through the outlet valve.

A more specific object is the provision of a conduit connecting the intake and delivery box, the conduit being of substantially smaller cross-sections than the diaphragm, thereby making for a short easy stroke without sucking air from the intake as the bilgewater recedes towards the level of the intake opening. With this particular relationship, there is provided a diaphragm of flexible, preferably resilient, material such as rubber, a reinforced stiff central portion overlying the upper end of the conduit, and a driving arm connected to the central portion so that the flexible portion will follow the stiff central portion.

Yet another object is the provision of an expandable chamber pump having a conduit connecting the chamber downwardly to a horizontal inlet and delivery box, and a flap-type inlet valve disposed substantially below the lower end of the conduit where it will be driven closed by the first downwardly surging water of the compression stroke, thereby utilizing substantially the entire surge of the compression stroke as a delivery force.

These and other objects will be apparent from the following specifications and drawings, in which:

Fig. 1 is a vertical section through the pump, and;

Fig. 2 is an end elevation as seen from the outlet end of the assembly.

Referring now to the drawings, in which like reference numbers denote the same or similar elements, 2 denotes a rectangular, elongated, hollow box, preferably formed of sheet metal, and having open inlet and outlet ends 4 and 6. Annularly apertured plates 8 are secured at the box ends for mounting threaded pipe fittings 10 for threaded engagement with the inlet and discharge pipes, which may be arranged to suit the needs of the particular problem. When the pump is used in the bilge of the boat, box 2 should be disposed at or near the lowermost portion of the bilge and the discharge pipe should lead outwardly of the boat above the water line.

Valve-seats 12, comprising annularly apertured, rectangular plates of the same width as the box 2 but somewhat longer than the height thereof, are welded as at 14 so as to be inclined in the same direction. It should be noted that one of the valve-seats 16 is disposed below the lower end of conduit 32, at least with regard to its lower end, for reasons specified below. Inlet and outlet valves 16 and 18 comprising rubber discs 20 are bolted as at 22 to the upper faces of the valve-seats to comprise flap valves. Discs 24 are riveted to the upper faces of the valves for loading and reinforcing the latter.

Box 2 is provided with an opening through the top wall in the region between valves, the opening being framed by an internally threaded fitting affixed to the top of the box for engagement with the lower end of a vertical conduit 32 threaded thereto as at 34. Conduit 32, which may be of considerable length, is threaded at 36 to a fitting 38 framing opening 40 which extends through the bottom of shell 42 which defines a chamber 44.

The chamber is provided with a top 46, the top and shell having cooperating flanges 48 bolted together as at 50 for clamping therebetween the edges of a flexibly resilient rubber diaphragm 52, which diaphragm extends across the chamber. A reinforcing ring 54 is affixed as by bolts 56 on the lower face of the diaphragm so as to overlie the upper end of conduit 40 and to engage shell 42 when the diaphragm is driven to its lowermost position. Bolts 56 extend through the diaphragm and on the upper side thereof are engaged with an upper plate assembly 58, which includes a pair of spaced, upstanding lugs 60, having slots therethrough for the reception of cross bolt 64.

Diaphragm 52 is driven through the cross bolt

44 sliding in horizontally extending lost motion slots 62 formed in the free end of a crank arm 66, the latter being pivoted by pin 68 to the top of 46 at the edge thereof. Crank arm 66 is further provided with a slot 70 for receiving removable handle 72 by which the crank arm may be rocked for vertically reciprocating the diaphragm.

As seen best in Fig. 2, top 46 is comprised of two spaced sections 46a and 46b, the sections being spaced to provide a well 74, the sides of the well being defined by side plates 76 secured to the top sections and having their lower edges arched as at 78 to conform to the contour of the top sections and to provide clearance for the diaphragm. Bearing plates 88 are secured to plates 76 adjacent to pivot pin 68.

In operation, handle 72 is pulled back to rock crank arm 66 about pivot pin 68, thereby lifting diaphragm 44 to operate the pump. Vertical movement of the diaphragm is obtained even though the free end of crank arm 66 partakes of an arcuate course because of lost motion slots 62. As the diaphragm is raised, inlet valve is opened by bilge water under atmospheric pressure and outlet valve 18 remains closed. When handle 72 is returned, diaphragm 44 is driven downwardly to compress or decrease the size of chamber 44 and the intake water surges against the upper surface of intake valve 16 to drive the latter shut, simultaneously opening outlet valve 18 and, in turn, driving the bilge-water out through the discharge pipe.

The cross sectional dimension of conduit 32 with respect to the area of flexible diaphragm 52 makes for a relatively easy stroke and avoids the tendency for the pump to suck air. It will be seen that most of the elements may be formed of sheet metal or stock pipes and fittings, and that its maintenance and cleaning are reduced to the minimum.

The invention, having been detailed above, is not to be limited by the specific showing but only in accordance with the scope of the following claims.

I claim:

1. In a pump of the type described, passage means forming an elongated substantially horizontal passage having inlet and outlet openings at opposite ends thereof, respectively, one-way valves operating in the same direction spaced along said passage, means defining a chamber above said passage, a diaphragm extending substantially horizontally across said chamber, means for reciprocating said diaphragm vertically whereby to expand and contract said chamber, and a substantially vertical conduit downwardly connecting the lower portion of said chamber and the portion of said passage between said valves, said conduit having a horizontal cross-section substantially smaller in area than the area of said diaphragm, said means defining the chamber comprising a rigid shell having upper and lower portions with the edges of the diaphragm clamped therebetween, said diaphragm being of flexible elastic material, a rigid reinforcing element disposed centrally of said diaphragm, said reinforcing element comprising a ring on the lower side of the diaphragm of a radial extent greater than the upper end of the conduit and overlying the latter, plate means on the upper side of the diaphragm overlying the ring and secured to the latter, upstanding lugs on the plate means, the means for reciprocating said diaphragm comprising a crank arm, lost motion slots disposed generally horizontally at one end of said crank arm, pivot means extending through said slots and said upstanding lugs, means pivotally connecting the other end of said crank arm to the edge of said shell, and a handle for rocking said crank arm.
2. The combination claimed in claim 1, wherein the upper portion of the rigid shell forming the chamber is provided with a well into which the handle for rocking said crank arm is adapted to be housed when in inoperative position.

THOMAS LANGAN.
